UNITED STATES PATENT OFFICE.

OTTO SPAHR, OF PHILADELPHIA, PENNSYLVANIA, ASSIGNOR TO STRAUSE GAS IRON CO., OF PHILADELPHIA, PENNSYLVANIA, A CORPORATION OF PENNSYLVANIA.

FLASH IGNITER FOR GAS BURNERS.

Application filed February 24, 1921. Serial No. 447,406.

To all whom it may concern:

Be it known that I, OTTO SPAHR, a citizen of the United States, and resident of Philadelphia, county of Philadelphia, State of Pennsylvania, have invented certain new and useful Improvements in Flash Igniters for Gas Burners, of which the following is a specification.

My invention relates to lighters for gas stoves and more particularly to that type thereof which are commonly referred to as flash igniters and which either occupy a fixed position in the gas stove for igniting any one or more of a series of gas burners in said stove at will or are movably arranged therein so that they may be selectively adjusted to ignite any one of said series of burners. Igniters of the type referred to usually contain, generally somewhere in the connection with the main gas supply pipe, a restricted passage or passages for supplying a reduced amount of fuel to the lighter, when not in use, for the purpose of maintaining what is commonly known as a pilot light. Because of the location of such passage or passages, considerable difficulty is encountered in drilling or otherwise providing the same and, because of inaccuracies in fitting, inefficient operation of the lighter oftentimes results therefrom, thereby adding to the cost of production and affecting the reliability of the device. Furthermore, said pilot light, which is more or less constantly burning at the nozzle end or burner thereof very often generates carbon very rapidly because of imperfect combustion whereby the efficiency of the lighter is very often still further interfered with. The particular object of my invention is to overcome these disadvantages and to provide a novel arrangement which is simple in construction and reliable and accurate in operation and in which the necessity for providing special restricted passages is entirely avoided, thereby increasing the efficiency of the device to a maximum extent. Another object of my invention is to provide a simple and novel arrangement whereby the formation of carbon is eliminated or at least reduced to a minimum and whereby the efficiency of the lighter is maintained at a maximum point. Other more specific objects of my invention will appear from the description hereinafter and the features of novelty will be pointed out in the appended claims.

Reference is to be had to the accompany-

ing drawings which illustrate an example of my invention without defining its limits and in which Figure 1 is a side elevation, partly in section, of a lighter embodying my invention; Fig. 2 is a sectional elevation on an enlarged scale; Fig. 3 is a plan view; Fig. 4 is a detail view of a washer included in my invention; Fig. 5 is an elevation, partly in section, showing another form of the invention; Fig. 6 is a plan view thereof; Fig. 7 is a sectional elevation on an enlarged scale; Fig. 8 is a detail view of the valve; and Fig. 9 is a perspective view of the nozzle.

For the purpose of describing the invention, I have chosen an igniter of the type which is generally arranged to swing in circular arcs to bring the firing head into cooperative relation with the gas burner which it is desired to ignite; it will be understood that this is only an example which is not intended to nor does it define the limits of the invention.

As shown in the drawings, the lighter comprises a supply tube 10 provided at its free end with a burner or nozzle which will be more fully referred to hereinafter and with a firing head 11 of any suitable construction, said tube 10 having its other end in screw-threaded connection with the boss 12 of a hollow plug 13 rotatably mounted in a valve casing 14 in the well known way and provided with a spring 15 which bears against the valve casing 14 with one end and against a head 16 carried by the plug 13 with its other end. The valve casing 14 is connected by means of a branch pipe 17 with the header or main supply pipe 18 of the gas stove in the well known way. As shown in the illustrated example, the plug 13 is formed with an axial passage 19 communicating with a transverse channel 20 which terminates at its outer end at an annular groove 21 formed on the plug in registry with the axial passage 22 of the branch whereby the valve casing is connected with the supply pipe 18. The axial passage 19 is formed at one end with a valve seat 23 and connected therewith the interior chamber 24 of the valve plug, said chamber being open at its outer end and being also in communication with the boss 12 and consequently with the tube 10. The open end of the interior chamber 24 may be closed by means of a screw-threaded bushing 25 in which the valve stem 26 is

slidably mounted and controlled by means of a spring 27 which engages said bushing at one end and with its other end abuts against a washer 28 carried by said stem; 5 the washer 28 is preferably provided with peripheral projections 29 arranged at spaced intervals to provide openings for the passage of the gas and to frictionally engage the inner surface of the plug 13 whereby said washer is held against any 10 material rotation and at the same time serves as a means for guiding the stem 26 in its axial movements. At its inner end, the stem is formed with a valve 30 which, 15 in co-operation with the valve seat 23, controls the flow of gas to the nozzle or burner, it being understood that this valve 30 is maintained in and returned to its normal position by means of the spring 27. In 20 the form shown in Fig. 5, the valve stem is in screw-threaded engagement with a collar 31 and is provided with an actuating head 32, the collar 31, by engagement with the bushing 25, arresting the inward movement of the stem 26 under the influence of 25 the spring 27 and thereby predetermining the normal position of the valve 30 with respect to the seat 23. The collar 31 is fixed against rotation by means of a fork 33 which extends adjacent to squared surfaces of said collar and beneath an annular flange thereof, said fork 33 forming part of 30 an operating handle 34 pivoted at 35 upon a suitable portion of the plug 13. The fork 33 in co-operation with the annular flange of the collar 31, and through the medium of the handle 34, also serves to adjust the valve 30 to its fully open position. 35 In the form illustrated in Figs. 1 and 2, the collar 31^a is provided with depending members 31^b which extend over opposite sides of the fork 33 and maintain the collar 31^a against rotation and at the same time provide a bearing against which the fork 40 45 bears during the operation of opening the valve. In this form, the valve stem 26 is screw-threaded to its free outer end and the head 32 is omitted, the stem itself being provided with a transverse cut for the accommodation of a suitable tool such as a 50 screwdriver, to facilitate the adjustment of said stem and its valve, as will be herein-after more fully described. The arrangement being described includes also a lock-nut 36 whereby the stem 26 is fixed in its 55 adjusted position against unintentional displacement.

In both forms, the stem 26 is adjusted in the collars 31 or 31^a to locate the valve 30 at a slight distance from the valve seat 23 in the normal condition of the parts; in other words, the closing movement of said valve is arrested, by engagement of the collar 31 or 31^a, with the bushing 25 before the seat 60 65 23 is reached. An annular orifice which

is always open is thereby provided between the valve and its seat and permits a sufficient amount of gas to pass to the tube 10 for maintaining a pilot light in operation at the firing head 11 or, more specifically, 70 at the burner or nozzle end of the tube 10. The dimensions of the annular orifice referred to may be varied by adjusting the valve stem 26 in the collars 31 or 31^a so as to provide a large or small pilot flame, as 75 may be desired.

As shown in the drawings, the supply tube 10 at its outer end, is in screw-threaded connection with a nipple 37 which is provided with a relatively reduced passage 80 38 into which the neck 39 of the nozzle 40 is frictionally fitted. The nozzle 40 is provided in its neck 39 with a passage 41 which diverges outwardly and terminates in a nozzle opening 42 and is constructed with an annular flange projecting axially from said nozzle to form a mixing chamber 43. The nozzle is further provided with air inlets 44 which communicate with the mixing chamber 43 and to which access is facilitated by inclining the end of the nipple 37, as indicated at 45. The arrangement may further include the previously mentioned hollow firing head 11 of any customary construction and provided in the well known 90 way with air inlets 46 and 47 and an exit opening 48 in registry with the nozzle 40; the firing head 11 is fitted upon the nipple 37 as shown in Figs. 1 and 5 and is fixed in position thereon in any suitable manner as, 100 for instance, by means of a screw 49.

The lighter is operated in the customary manner; that is to say, it may be swung in an arc having the plug 13 as a centre to bring the firing head 11 and with it the nozzle opening 42 into co-operative relation with the burner which it is desired to ignite. After this adjustment has been had, the handle 34 is depressed in the well known 105 way to move the valve 30 in a direction away from the seat 23 whereby the amount of gas which reaches the nozzle opening 42 is temporarily increased and a correspondingly enlarged flame is produced whereby the gas 110 at the selected burner is ignited. As soon as pressure upon the handle 34 is removed, the valve will be returned to its normal position by the action of the spring 27, it being understood that the return or closing movement of said valve is never sufficient, 115 because of the adjustment of the stem 26 in the collar 31 or 31^a, to completely shut off the supply of gas to the firing head 11. By properly adjusting the stem 26 in the collar 31 or 31^a, the valve 30 may be caused to engage the seat 23, thereby cutting off completely the gas supply to the nozzle. This adjustment permits the pilot light to be shut off, thus saving the fuel which otherwise would be consumed thereby and may be 120

utilized if, for any reason, the gas stove or its equivalent, of which the igniter is a part, is to remain idle for a period of time as, for instance, in case the housewife has 5 occasion to leave town for any length of time.

In practice, gas passes through the nozzle opening 42 into the mixing chamber 43 and there becomes mixed with air which enters said chamber through the air inlets 44 and provides a highly combustible mixture which results in substantially perfect combustion and a substantially perfect flame. This is true when the flame is in the form 15 of a pilot light and also when it comprises a flash as the valve 30 is opened for the purpose of igniting one of the gas burners. The formation of carbon and accumulation thereof is therefore substantially eliminated 20 and the reliability and efficiency of the lighter correspondingly increased. In the preferred form, the nozzle 40 is constructed of aluminum or a similar metal as an element independent of the nipple 37 and is 25 operatively combined therewith simply by means of friction so as to be readily removable if, for any reason, this becomes necessary. While the described arrangement is particularly adapted for use in connection 30 with flash igniters of the type referred to, it will be understood that it may be efficiently utilized in combination with other forms and types of burners. The described arrangement particularly avoids all necessity 35 for the provision of special passages for maintaining a pilot light in operation and reduces the construction to the utmost simplicity and at the same time, makes the regulation of the pilot light a simple matter. The latter is due to the fact that the 40 outer end of the stem 26 is, generally speaking, in a readily accessible location; at the same time, a novel and highly efficient nozzle or burner construction is also provided. 45

In many cases, the construction of the gas stove and the arrangement of the parts thereof, makes it necessary to install the lighter therein in a reversed position or, in 50 other words, upside down with respect to the position usually occupied thereby. To provide for this, the handle 34 may be con-

structed of sheet metal and in a manner so as to be reversible upon the plug 13, thus at all times exposing a surface α to view which is of finished appearance and efficient 55 for the intended purpose.

Various changes in the specific form shown and described may be made within the scope of the claims without departing 60 from the spirit of my invention.

I claim:

1. A gas lighter comprising a valve casting connected with a source of gas, a plug rotatably mounted therein, a supply tube carried by and communicating with said plug, a burner carried by said tube, a valve seat in said plug, a valve slidably mounted therein to control the flow of gas to said burner, a stop adjustably mounted upon said valve whereby the closing movement thereof 65 is arrested at a distance from said seat to provide a restricted passage for supplying a reduced amount of gas to said burner to maintain a pilot flame thereat and a handle 70 for actuating said valve.

2. A gas lighter comprising a valve casting connected with a source of gas, a plug rotatably mounted therein, a supply tube carried by and communicating with said plug, a burner carried by said tube, a valve seat in said plug, a valve stem slidably mounted therein and projecting outwardly beyond the same, the projecting end of said stem being externally screw-threaded, a 75 valve at the inner end of said stem for controlling the supply of fuel to said burner, an internally screw-threaded stop adjustably mounted upon said stem for arresting the closing movement of said valve at a distance from said seat whereby a restricted 80 passage is provided for supplying a reduced amount of gas to said burner to maintain a pilot flame thereat, a lock nut for locking said stop in an adjusted position, and a 85 forked handle pivoted on said plug and projecting beneath said stop for actuating said valve and whereby said plug and its associated elements may be pivotally adjusted 90 relatively to said casing.

In testimony whereof I have hereunto set 100 my hand.

OTTO SPAHR.
